UNITED STATES PATENT OFFICE.

BENJAMIN F. NEELY, OF COLTON, CALIFORNIA.

SPRING BED-BOTTOM.

SPECIFICATION forming part of Letters Patent No. 541,004, dated June 11, 1895.

Application filed April 10, 1895. Serial No. 545,232. (No model.)

To all whom it may concern:

Be it known that I, BENJAMIN F. NEELY, a citizen of the United States, and a resident of Colton, in the county of San Bernardino and 5 State of California, have invented certain new and useful Improvements in Spring Bed-Bottoms; and I do hereby declare the following to be a full, clear, and exact description of the invention, such as will enable others skilled 10 in the art to which it appertains to make and use the same.

My invention relates to improvements in spring bottoms for beds, the object of the same being to provide a device of this character 15 which forms a resilient support for the mattress and at the same time prevents sagging at any of the parts.

The invention consists of a frame having a series of coiled hooked springs secured at the 20 top and bottom ends thereof, and may have two or more similar springs secured to the side bars of the frame. These springs as stated, are formed with upwardly projecting hooks to which are attached the frame work 25 made up of outer wires suitably connected together, and a series of cords or wires running lengthwise of the bed connected at intervals by means of loops or hooks forming them in the nature of a woven bed. None of 30 the cords, however, cross one another, the connections between them being made by said loops. Passing transversely of this frame and connecting the side wires, are a pair of wire connecting bars, to which are attached 35 coiled springs extending downwardly and resting upon a removable bar connecting the side beams of the spring frame. I may, if I desire, have the inner beams of the bed in 40 which this frame is adapted to be inserted formed with metal brackets adapted to receive the ends of the frame and thereby hold the same in place. In order to prevent further sagging I may also connect the cords from any two points by cords or wires, which 45 may be tightened or loosened for the purpose of increasing or decreasing the tension of the springs.

The invention also consists in other details of construction and combinations of parts 50 which will be hereinafter more fully described and claimed.

In the drawings forming a part of the speci-

fication, Figure 1 represents a top plan view of my device. Fig. 2 is a vertical central section through the same.

55

Like reference-numerals indicate like parts in the various views.

By reference to the drawings it will be seen that my spring bed bottom is formed of side beams 1, 1, and end beams 2, 2. The lower 60 ends of the side beams 1 are formed with an inwardly projecting flange or ledge 3 upon which rests and is adapted to slide into and out of place in guides 4 the cross bar 5. The upper edges of the end beams 2 have secured 65 in them a series of single or double coiled springs 6, 6, having an upwardly projecting hook 7 formed at one end thereof. Similar coiled hooked springs may be located along the upper edges of the side bars 1. The mat- 70 tress supporting frame is made up of rods or wires 8, 8, adapted to fit over the hooked ends 7 of the springs 6 on the end beams 2, and of side connecting bars or rods 9 which will fit over the hooked springs upon the side bars 1, 75 provided such springs are employed on said side bars. These wires or rods 8 and 9 are connected at their outer ends by the formation of a loop, and a cord 10 is wound around the hooks 7 and rods 8 and 9, forming a woven 80 top, the said cords being connected at the points of meeting by loops or rings 11, 11. None of the cords cross one another, the connection between the two adjacent parts being by the hooks or rings 11 solely. Connecting 85 the rods or wires 9 and extending transversely across the frame are a pair of wires or rods 12 to which are connected by loops or rings 13 coiled springs 14 resting at their lower ends upon the cross bar 5. These coiled springs 90 13 are also connected to one another at their upper ends and to the side bars 9 by loops or rings 15. These are provided for the purpose of adding resiliency to the bed bottom and to prevent sagging of the same at the center. 95 If, however, it is found at any time that it is not desired to use the same, the bar 5 may be removed from beneath said springs by sliding the same in the guide 4, and the bottom be supported entirely by the frame resting upon 100 the hooks 7 of the springs 6.

Having now described my invention, what I claim as new, and desire to secure by Letters Patent, is—

1. The herein described spring bottom for beds, consisting of a frame made up of side and end beams, a series of coiled hooked springs secured in said end frames, and a bottom proper adapted to fit upon and be supported by said hooked springs, consisting of wire end and side rods and a series of cords woven upon said side and end bars, connected to said hooks, and the adjacent parts of said cords connected by rings or loops, substantially as described.
2. The herein described spring bottom for beds, consisting of a frame made up of side and end beams, a series of coiled hooked springs secured in said end frames, and a bottom proper adapted to fit upon and be supported by said hooked springs, consisting of

wire end and side rods, and a series of cords woven upon said side and end bars connected to said hooks and the adjacent parts of said cords connected by rings or loops, transverse rods connecting said side rods, coiled springs secured thereto and resting upon a movable bar moving in guides along the inner edges of said side beams, substantially as and for the purpose described.

In testimony whereof I have signed this specification in the presence of two subscribing witnesses.

BENJAMIN F. NEELY.
